UNITED STATES PATENT OFFICE.

JOHN BRUEHNE, OF DENVER, COLORADO.

AUTOMOBILE-LOCK.

1,203,476.

Specification of Letters Patent. Patented Oct. 31, 1916.

Application filed October 11, 1915. Serial No. 55,170.

To all whom it may concern:

Be it known that I, JOHN BRUEHNE, a citizen of the United States, residing in the city and county of Denver and State of Colorado, have invented certain new and useful Improvements in Automobile-Locks; and I do declare the following to be a full, clear, and exact description of the invention, such as will enable others skilled in the art 10 to which it appertains to make and use the same, reference being had to the accompanying drawings, and to the characters of reference marked thereon, which form a part of this specification.

15 This invention relates to improvements in lever locking devices, and while it may obviously be employed in other relations, it is particularly applicable as a positive locking means for the control levers of automobiles, 20 especially of the central control type, or types having a similar arrangement of levers.

City ordinances, in large communities, now quite generally prohibit the positive 25 locking of machines against instant removal in cases of emergency, and this is more forcibly true in the crowded, down-town fire districts. As a result, machines are left standing carelessly unprotected against theft, 30 which frequently occur even during the busiest hours of the day or night, outside of theaters, etc., and to partially overcome this evil, locks have been provided for the transmission control lever, to maintain the transmission 35 control lever out of gear, but prior to my invention the importance of a coöperating brake lever lock, has not been considered essential or desirable, and in fact has been so stated in prior patents.

40 It is true that a degree of safety is afforded by a transmission lock alone, but in sparsely settled residence sections, such as outlying suburbs, or on outing trips to the country or elsewhere, where the fire and 45 police ordinances do not prevail, if a machine is left standing unattended for any length of time, or overnight, such locks are manifestly highly inefficient, as machines have frequently been towed away, or caused 50 to run away from high winds, initial displacement on steep hills, or from other causes.

The primary object of my invention, therefore, is to overcome these objections 55 effectively, in a simple and comparatively in-

expensive manner, and broadly consists in providing a lock controlled lever shackle, serving, as a unitary device, the dual functions of locking one lever independently of or conjointly with another as desired, and 60 which may be readily applied to old as well as new cars.

Other advantages will appear from the following specification, and having thus generally outlined the broad principles of 65 the invention, a practical, although not necessarily limited, form of the same will now be described more in detail, reference being had to the accompanying drawings, in which like characters designate the same parts in 70 the several views, and in which—

Figure 1, is a top plan view of the applied device, the levers appearing in cross section, and the parts being shown in conjoint locked relation in full lines. The unlocked arrangement of the brake lever is shown, in dotted lines, at the right hand side of the view, and the shackle folded back out of the way, at the left hand side. Fig. 2, is a top plan detail view of the detached device, 80 a portion of the locking arms being shown in section, and Fig. 3, is a view in side elevation, looking in the direction of the arrow 3, in Fig. 1.

5 designates a base plate, secured to a 85 portion of the automobile base or floor by any suitable means illustrated simply by screws 6. This plate has an elongated slot 8, alining with a similar slot in the car body, to permit of the operation of the brake lever 90 9, a suitable aperture being also provided to permit the transmission control lever 7 to be disposed in operative relation with the transmission mechanism in the usual way, but the contour of this aperture is dependent 95 upon the type of car, and whether the transmission lever has a varying back and forth and sidewise oscillatory movement, as when a universal bearing is employed, or has a straight linear motion, in which latter instance the aperture would necessarily be an elongated slot.

The improved shackle itself may be generally designated by the numeral 10, and consists of a main body portion member 12, 105 provided with open-faced slots or pockets, of suitable contour, to separately receive the transmission and brake control levers, and closing means, designated at 13, comprising shackle arms operatively associated with the 110

open faces of said pockets to close one of said pockets independently of or conjointly with the other of said pockets as desired.

It may be stated here that the member 12 5 may be provided with a short, angularly and downwardly disposed, shank 14, pivotally connected, as at 15, with a metal strap 16, secured in any suitable way, illustrated by bolts 17, passing through apertures 18, 10 and secured to the floor base 19. In the drawings, the base plate 5 is shown as mounted on the top of the transmission case 38, projecting slightly above the floor, so that a space is provided for receiving the 15 shackle neatly and compactly, when folded back out of operative association with the levers, in a substantially flush position with reference to the floor plane.

As previously stated, the member 12 is 20 provided with open faced pockets, and while the exact formation is not essential, these open faced pockets may be formed by suitable narrow spaced extensions projecting from the rear of a central enlarged portion 21 and forwardly disposed as shown, one of 25 which extensions may be apertured, as at 30, providing a locking eye 27 hereinafter referred to. To the other extension one of the shackle arms 24, of the closing means 18, 30 may be pivoted, as at 20, the said shackle arm being apertured, as at 23, to encompass a locking staple 22, mounted on the forward face of the enlarged portion 21. A second shackle arm, of the closing means, is designated at 25, and is apertured, as at 28, to encompass the eye 27 in locking relation.

By way of illustration, in the drawings the shackle arms 24 and 25 are shown hingedly connected, forming a pivotal joint or articulated connection substantially intermediate of the open faced slots, but in the broadest sense of the invention, the actual shackling means might be varied within wide limits without vitiating the essential 45 features of the device, including means functioning to accomplish the two-fold result of shackling one of the levers independently of or conjointly with the other lever as desired.

50 29 simply designates suitable securing means, such as a padlock, the shackle or bow of which is adapted to engage the locking staple 22, or the locking eye 27, dependent upon whether one or both levers are to be locked.

In practice, it may be desirable to so construct the member 12 as shown, in order that the part 21 may extend between the levers, but this obviously may be varied, especially 60 where there is insufficient space between the levers.

From the drawings and foregoing complete description, the operation will be clear, yet it may be briefly stated that, when the 65 shackle is in its folded-back position, shown

in dotted lines at the left of Fig. 1, it may at will be swung forwardly, through its pivotal connection 15, into operative position, with both shackle arms open. To lock the transmission lever 7, leaving the brake lever 70 9 free to be operated, the lever 7 having been moved to its off-position is disposed in its complementary open-faced pocket, whereupon the shackle arm 24 is swung to its closed position, and the padlock applied to 75 the staple 22, the open position of the shackle arm 25 being indicated in dotted lines at the right of Fig. 1. If, however, the brake lever 9 is also to be locked, it is positioned in its complementary open-faced pocket, in brake 80 applied position, when the arm 25 is moved to close the pocket, the slot 28 encompassing the locking eye 27, and the padlock 29 is applied to this eye, as shown in full lines, instead of to the staple 22. However, the invention is not necessarily restricted to the detailed arrangement illustrated, excepting as limited by the scope of the claims, for it is manifest that a fair range of equivalent elements may be employed without departing from the generic idea, which consists chiefly in providing suitable means for shackling one lever (the transmission control lever) independently of and also conjointly with a second lever (the brake lever) as desired, but having fully disclosed the nature of the invention and its mode of operation, the particular features of novelty will now be more succinctly stated.

What I claim, is:—

1. In a locking device substantially as described, a suitably secured shackle, comprising a base member in proximate relation to and extending transversely across the levers to be locked, shackling means coöperating 105 with said base member to encompass said levers in locking relation, and means for positively locking said shackling means in relative positions to secure one of said levers against movement independently of the other or conjointly therewith as desired.

2. In a locking device substantially for the purpose described, a shackle, comprising a base member in proximate location to and extending transversely across the levers to be locked, pivotally associated shackling means coöperating with said base member to encompass said levers in such relation as to hold one of said levers against movement independently of the other or conjointly therewith as desired, and means for positively locking said shackling means in either of the aforesaid relations.

3. In a locking device substantially for the purpose described, a shackle, comprising a base member having a recessed face adapted to receive the levers to be locked, shackling means coöperating with the recessed face of said base member to encompass said levers in such relation as to hold one of said

levers against movement independently of the other or conjointly therewith as desired, and means for positively locking said shackling means in either of the aforesaid relations.

4. In a locking device substantially for the purpose described, a shackle, comprising a base member having a pair of open-faced pockets, each pocket being independently in line with and adapted to receive its complementary lever to be locked, means co-operating between said base member and the open faces of said pockets to close the open face of one pocket independently of the other 15 pocket, and also the open face of the other pocket conjointly therewith, as desired, and locking means for said closing means, in either of the aforesaid closed positions.

5. In a locking device substantially for 20 the purpose described, a shackle, comprising a base member having a pair of open-faced pockets, each pocket being independently in line with and adapted to receive its complementary lever to be locked, shackling means 25 operable over the open faces of said pockets and adapted to close the open face of one pocket independently of the other and also to close the open face of the other said pocket conjointly therewith as desired, and 30 co-operating means, including a single lock, for positively locking said shackling means in either of the aforesaid positions.

6. In a locking device substantially for the purpose described, a shackle, adapted to be 35 secured in proximate relation with the levers to be locked, and having a pair of open-faced pockets, each pocket being independently in line with and adapted to receive its complementary lever, shackling means 40 pivotally associated with said base member to encompass said levers in such relation as to hold one of said levers against movement independently of the other said lever or conjointly therewith as desired, and means for 45 positively locking said shackling means in either of the aforesaid relations.

7. In a locking device substantially for the purpose described, comprising a base mem-

ber adapted to be suitably secured proximately to the levers to be locked, means co-operating with said base member for shackling one lever both independently of and conjointly with the other lever, said co-operating means consisting of a jointed shackling element, and means for positively locking said jointed shackling element in either of the aforesaid relations desired, including locking elements for said shackling means, and a key controlled lock for said locking elements.

8. In a locking device substantially for the purpose described, a base member adapted to be suitably secured proximately to the levers to be locked and extend transversely across the same, a jointed shackling element co-operating with said base member to encompass said levers in such relation as to hold one of said levers against movement independently of the other said lever or conjointly therewith as desired, and means for 70 positively locking said shackling element in either of the aforesaid relations.

9. In a locking device substantially for the purpose described, a base member adapted to be suitably secured proximately to the 75 levers to be locked and extend transversely across the same, a two-part articulated shackling member, pivoted at one end to said base member and co-operating therewith to encompass said levers in locking relation, 80 locking elements between said base member and shackling member, substantially intermediate of said articulate and pivotal connections, to permit of the locking of one lever independently of the other, locking elements 85 between said base member and the free end of said shackling member, to permit of the locking of both levers conjointly, and a lock for said locking elements.

In testimony whereof I affix my signature 90 in presence of two witnesses.

JOHN BRUEHNE.
